(57) **CLAIM**

The ornamental design for a dental prosthetic, as shown and described is claimed.

DESCRIPTION

FIG. 1 is a perspective view of a first embodiment of a dental prosthetic of the present invention;

FIG. 2 is a front plan view of the dental prosthetic shown in FIG. 1;

FIG. 3 is a rear plan view of the dental prosthetic shown in FIG. 1;

FIG. 4 is a right side view of the dental prosthetic shown in FIG. 1;

FIG. 5 is a left side view of the dental prosthetic shown in FIG. 1;

FIG. 6 is a top plan view of the dental prosthetic shown in FIG. 1; and,

FIG. 7 is a bottom plan view of the dental prosthetic shown in FIG. 1.

The broken lines immediately adjacent the claimed areas represent the bounds of the claim, and all other broken lines are included for the purpose of illustrating portions of the present invention that form no part of the claimed design. None of the broken lines form part of the claimed design.
